THE NORRIS PETERS CO., PHOTO-LITHO., WASHINGTON, D. C.

UNITED STATES PATENT OFFICE.

AXEL C. BERNTZEN, OF EUGENE, OREGON.

AUTOMATIC CHICKEN-FEEDING MACHINE.

1,214,881.

Specification of Letters Patent.

Patented Feb. 6, 1917.

Application filed February 9, 1915. Serial No. 7,202.

To all whom it may concern:

Be it known that I, AXEL C. BERNTZEN, a citizen of the United States, residing at Eugene, in the county of Lane and State of Oregon, have invented certain new and useful Improvements in Automatic Chicken-Feeding Machines, of which the following is a specification, reference being had therein to the accompanying drawing.

10 This invention relates to automatic chicken feeding machines and has for its principal object the production of a device which is so constructed as to intermittently distribute a quantity of food carried thereby.

15 Another object of this invention is the production of a chicken feeding machine in which a number of cans are pivotally mounted so that when they are released they will independently swing downwardly for emptying the food carried thereby, said cans being provided with a simple means for intermittently releasing the same.

20 Another object of this invention is the production of an automatic chicken feeding machine wherein simple and efficient operating mechanism is provided for automatically swinging the trip arms for intermittently releasing the cans whereby the food positioned within the cans may be emptied therefrom.

25 With these and other objects in view, this invention consists of certain novel combinations, constructions, and arrangements of parts as will be hereinafter fully described and claimed.

30 In the accompanying drawings:

Figure 1 is a side elevation of the automatic chicken feeding machine as constructed in accordance with this invention.

40 Fig. 2 is a side elevation of the operating portions of the machine, portions of the device being broken away.

45 Fig. 3 is a section taken on the line 3—3 of Fig. 2 looking in the direction of the arrows.

Fig. 4 is a vertical section through a portion of the machine illustrating the manner in which the cans are supported.

50 Fig. 5 is a top plan view of the upper platform illustrating the manner in which the motor is carried thereby, a portion of the cover plate being broken away.

Fig. 6 is a fragmentary detailed perspective view of the upper platform illustrat-

ing the manner in which one of the trip arms is supported.

Fig. 7 is a vertical sectional view through one of the cans.

Fig. 8 is a detailed perspective view of a certain pivot bracket used for pivotally mounting the cans upon the device.

Fig. 9 is a fragmentary sectional view through the upper platform illustrating the manner in which the motor is carried thereby.

Fig. 10 is a top plan view of a certain drive wheel used in connection with this invention.

Referring to the accompanying drawings by numerals it will be seen that the automatic chicken feeding machine comprises a lower platform 1 and an upper platform 2. These platforms 1 and 2 are preferably made of wood. However, it is, of course, obvious that they may be made of any other suitable material. They are reinforced about their outer peripheries by means of the metallic bands 3 which efficiently reinforce the same and also reduce the friction thereon as well as the wear when the device is in use. The supporting standards 4 radiate toward their lower ends and are adapted to have their ends suitably secured to the lower platform 1. The upper ends of the standards may fit into sockets formed in the platform 1, so as to be quickly detached therefrom if desired. A plurality of curved fingers 5 have laterally bent ends 6 extending therefrom, these ends being secured in any suitable manner to the lower surface of the lower platform 1, whereby the outer ends of the fingers 5 will extend for a considerable distance beyond the plane of the outer peripheries of the lower platform 1, as shown in Figs. 1 and 2.

A plurality of supporting rods 7 pass through the lower platform 1 and are secured in place by means of the nuts 8, whereby these rods 7 will extend for a considerable distance within the lower platform 1 for the purpose of retaining the upper platform 2 in its correct position. These rods 7 are provided with heads at their upper ends as shown at 9 in Fig. 5 whereby the upper platform is held against accidental displacement, and will, therefore, be retained in alinement with the lower platform 1.

A pair of strips 10 are folded upon the upper sections of the lower platform 1 as shown at 11, so as to extend at right angles to each other. One of the strips 10 is provided with a raised portion 12 which will fit upon the other strip 10 thereby allowing the body portion of the strip to rest snugly upon the upper surface of the lower platform. These strips terminate at their ends in vertically extending portions 13 through which the supporting strands 14 pass. It is upon these strands 14 that the cans are pivotally supported and, therefore, these strands are carried at a spaced distance above the upper surface of the lower platform, as clearly shown in Fig. 4. Each can comprises a body 15 having a bottom 16 to which the pivot bracket 17 is fixedly secured. This pivot bracket has spurs 18 struck from the body thereof so as to pass through the bottom 16 of the can 15 thereby fixedly retaining the bracket in engagement with the can. The depending portions 19 of the bracket are provided with registering openings 20 through which the strands 14 pass for pivotally supporting the can in engagement therewith. A plate 21 is fixedly secured by means of the rivets 22 to the inner portions of the body 15 of each can, these plates having their upper ends 23 extending for a considerable distance above the upper portions of the can. In order to hold these cans against accidentally swinging or remaining normally in an inverted position, the upper platform 2 is provided with a plurality of trip arms 24. These trip arms 24 are held in pivotal engagement with the outer portions of the upper platform so as to bear upon the bands 3 extending therearound. A screw 25 passes through the trip arms and bands and into the upper platform so as to pivotally support the trip arms. A second screw 26 is carried by the upper platform adjacent to the side portion of the trip arms, thereby limiting the pivotal movement of the particular trip arm in each direction. When the cans are in their correct position on the strands 14 and are filled with any desired food they will extend substantially upwardly so as to cause the upper end portion 23 of each plate 21 to bear against the stoppins 27 carried by the lower portions of the upper platform 2. The trip arms 24 depend for a distance below the lower surface of the upper platform so as to engage the upper portions 23 of the plates 21 thereby releasably retaining the said cans in their correct position for retaining the food carried thereby. It will be noted that the stoppins 27 are carried so as to engage the plates retaining the cans against swinging inwardly toward the center portions of the platform and causing the food carried by the cans to be emptied upon the inner por-

tions of the lower platform. These stoppins retain the can in a slanting position as clearly shown in Fig. 4 so that the cans are supported off-center whereby when the trip arms are swung the weight of the can will cause the same to swing downwardly and thus empty the food carried thereby upon the particular curved fingers 5 carried therebeneath, which will in turn spread or distribute the food which is emptied thereon. 75

In order to intermittently swing the trip arms 24 the upper platform 2 is provided with a pocket 28. This pocket 28 carries a suitable motor 29 adapted to be operated by the key 30. This motor 29 which is preferably of a spring construction has a pinion 31 which is in mesh with the drive cog wheel 32 carried at one corner of the motor 29 in any suitable manner. This drive wheel 32 is provided with a trigger 33 which extends thereabove and then to one side so as to allow its outer end to overhang the outer periphery of the upper platform 2. Therefore, when the drive wheel 32 is rotated by means of the pinion 31 it will impart rotary motion to the trigger 33 by swinging the same in a circle. As the outer end of this trigger 33 comes into engagement with the upper ends of the trip arms 24 it will be seen that the trip arms will be independently swung to one side so as to allow their lower ends to release the upper end of the particular plate 21 which engages the same whereby one of the cans will be allowed to swing downwardly for emptying the contents thereof. It will be seen that the drive cog wheel 32 is provided with a ratchet wheel 34 which is loosely mounted thereon in any desired manner, and which is engaged by the pawl 35 pivotally mounted upon the wheel 32. A spring 36 is carried by the wheel 32 so its outer edges are bent as shown at 37, to bear upon the pawl 35 thereby releasably retaining the pawl in engagement with the ratchet wheel 34. This ratchet wheel 34 is, as above stated, loosely mounted upon the wheel 32 and this wheel 32 is keyed to the trigger 33, therefore, the rotation of the wheel 32 in one direction will cause the pawl 35 to bear upon the ratchet wheel 34 for imparting rotary motion to the trigger 33. If, however, it is desired to swing the trigger 33 independently of the motor drive wheel 32, the trigger may be swung in the opposite direction so as to cause the ratchet wheel 34 to pass by the pawl 35 without moving the drive wheel 32. The motor 29 is retained in a set position within the pocket 28 by means of the sunk plates 38 which are retained in engagement with the motor 29 and the upper platform 2 by means of the screws 39. This upper platform 2 is adapted to be covered by a removable sheet cover 40 which is adapted to cover the entire up- 130

per portion of the upper platform thereby inclosing the pocket 28, the motor 29, and the other operating elements for the trigger 33. Therefore, dirt is prevented from covering the upper platform and passing into the operating elements so as to cause the same to operate less efficiently. The hanger brackets 41 are carried by the lower portions of the upper platform 2 so as to extend for a considerable distance beyond the outer peripheries thereof, and these hanger brackets 41 are provided with upturned outer ends 42 whereby these brackets may support the hood 43 above the upper platform 2. Therefore, while this hood is detachably supported when it is carried by the hanger brackets 41 it will protect the cans and upper platform from the weather when the device is used out of doors and will also prevent the fowls which may fly thereacross from accidentally engaging the trip arms and thereby cause the cans to accidentally empty the contents carried thereby.

When this device is in operation the hood may be removed so as to allow the cans to be easily swung upwardly whereby the trip arms 24 may be swung for engaging the plates 21 thereby releasably retaining the cans in their correct positions for retaining the contents carried thereby. The motor may be wound by means of the key 30 and then the cans may be filled. The hood may then be replaced upon the hanger brackets 41, at which time the device is in operation. It is, of course, obvious that the motor 29 may be geared so as to swing the trigger 33 as rapidly as desired, which is preferably about one revolution every eight or ten hours. As the trigger 33 comes into engagement with the trip arms, it will swing the same until the motion is limited by the adjacent pin 26. The can being supported off-center will swing downwardly, thereby emptying the food therefrom.

From the foregoing description it will be seen that a very simple and efficient automatic chicken feeding machine has been produced, wherein the food carried by the cans will be easily emptied therefrom whenever the cans are released, whereby only a predetermined amount of food may be distributed for use.

What is claimed is:

1. In an automatic chicken feeding machine the combination of a support, a plurality of cans pivotally mounted upon said support, and means for releasably engaging said cans for releasing the same thereby causing the cans to be swung so as to empty the food carried thereby.

2. In an automatic chicken feeding machine, the combination of a support, a plurality of cans pivotally mounted upon said support, a plurality of trip arms mounted upon said support, and means for operating

said trip arms so as to release said cans whereby the cans may be swung for emptying the food carried thereby.

3. In an automatic chicken feeding machine, the combination of a support, trip arms pivotally mounted upon said support, a plurality of cans pivotally mounted upon said support, a trigger carried by said support, means for swinging said trigger in a circle, said trigger being adapted to engage said trip arms so as to swing the same to one side at intermittent intervals, whereby the trip arms will release said cans for allowing the cans to swing downwardly thereby distributing the food which is emptied therefrom.

4. In an automatic chicken feeding machine, the combination of a support, a plurality of strips carried by said support and terminating in vertically extending ends, a strand carried by said vertically extending ends, a plurality of cans pivotally mounted upon said strand, means for releasably retaining said cans in a set position, said means being adapted to release said cans so as to allow the same to swing downwardly whereby the contents of the can will be emptied therefrom.

5. In an automatic chicken feeding machine, the combination of a support, a plurality of strips mounted upon said support and terminating in vertically extending ends, a strand carried by said vertically extending ends, a plurality of cans positioned above said strand, a pivot bracket positioned upon the lower portion of the can, each pivot bracket provided with spurs passing through the lower portion of the can whereby the pivot bracket will be fixedly retained in engagement with the can, said pivot bracket having depending portions provided with alined openings, said strand passing through said alined openings whereby the can will be pivotally mounted upon said strand, and means for releasably retaining said cans in a set position whereby the said means may release said cans for allowing the same to swing downwardly for distributing food carried thereby.

6. In an automatic chicken feeding machine, the combination of a lower platform, an upper platform positioned above the lower platform, means for supporting said upper platform at a spaced distance from the lower platform, a plurality of cans supported upon said lower platform, a plurality of trip arms pivotally mounted upon said upper platform, said trip arms being adapted to releasably retain said cans in a set position, and means for swinging said trip arms whereby said cans may be released at intermittent intervals, for emptying the contents carried thereby.

7. In an automatic chicken feeding machine, the combination of a lower platform,

- 4
- means for supporting said lower platform, an upper platform positioned above said lower platform, means for supporting said upper platform at a distance above the lower platform, a plurality of cans pivotally mounted upon said lower platform, a plurality of trip arms pivotally mounted upon the outer periphery of said upper platform, said trip arms being adapted to 5 releasably retain said cans in a set position, a trigger pivotally mounted upon said upper platform, means for swinging said trigger in a circle, said trip arms positioned in the path of travel of said trigger 10 whereby said trip arms may be swung by said trigger so as to release said cans, whereby the cans will swing downwardly for emptying the contents carried thereby at intermittent intervals.
- 15 20. 8. In an automatic chicken feeding machine, the combination of a lower platform, means for supporting said lower platform, an upper platform positioned above said lower platform, means for supporting said upper platform above said lower platform, a plurality of cans pivotally mounted upon said lower platform, means carried by said upper platform for preventing said cans 25 from swinging inwardly toward the central portion of said platform, said means being adapted to hold the cans so that they will be supported offcenter, means for releasably retaining said cans in a set position, means for intermittently operating said last-mentioned means, whereby the cans may be released so as to swing downwardly for emptying the contents carried thereby.
- 30 35. 9. In an automatic chicken feeding machine, the combination of a lower platform, means for supporting said lower platform, an upper platform positioned above said lower platform, means for supporting said upper platform at a distance above the lower platform, a plurality of cans pivotally 40 mounted upon said lower platform, a plate fixedly carried within each of said cans and extending for a distance thereabove, a plurality of stop-pins fixedly carried by said upper platform and engaging the forward portions of said plates whereby said cans will be prevented from swinging to a vertical position so that each can will be supported offcenter, means carried by said upper platform for releasably retaining said cans in a set position, and means for operating said last-mentioned means, whereby said cans may be released by said means so as to 45 swing downwardly for emptying the contents carried thereby.
- 50 55. 10. In an automatic chicken feeding machine, the combination of a lower platform, means for supporting said lower platform, an upper platform positioned at a distance above the lower platform, means for supporting said upper platform at a distance 60 above the lower platform, a plurality of strips carried upon the lower platform and terminating in vertically extending ends, a strand carried by said strips, a plurality of cans pivotally mounted upon said strand, a plurality of trip arms pivotally mounted upon the outer periphery of said upper platform, means for limiting the internal movement of said cans whereby said cans will be supported offcenter, and means for 65 intermittently swinging said trip arms whereby said cans may be intermittently released so as to swing downwardly for emptying the contents carried thereby.
- 70 75 80. 11. In an automatic chicken feeding machine, the combination of a lower platform, means for supporting said lower platform, an upper platform positioned above said lower platform, a plurality of cans pivotally carried by said lower platform, a plurality of trip arms pivotally mounted upon the outer periphery of said upper platform, said trip arms releasably retaining said cans in set positions, said upper platform being provided with a pocket, a motor carried with 85 in said pocket, a drive wheel carried by said pocket, said motor being adapted to operate said drive wheel, a trigger extending into said pocket, means carried by said drive wheel for swinging said trigger in a circle 90 when said drive wheel is rotated, said trip arms being positioned in the path of travel of said trigger whereby said trip arms will be intermittently swung to one side for releasing said cans for allowing the cans to 95 swing downwardly at intermittent intervals for emptying the contents carried thereby.
- 100 110. 12. In an automatic chicken feeding machine, the combination of a lower platform, means for supporting said lower platform, a plurality of cans pivotally mounted upon said lower platform, means for releasably retaining said cans in a set position, a plurality of curved fingers fixedly mounted upon the lower portions of said platform and extending outwardly therefrom, said fingers being positioned in alinement with said cans, and means for actuating said last-mentioned means for releasing said cans at 115 intermittent intervals whereby the cans will swing downwardly for emptying the contents carried thereby upon said fingers, whereby the contents will be distributed.
- 115 120. 13. In an automatic chicken feeding machine, the combination of a lower platform, supporting standards engaging said lower platform, a plurality of strips terminating in vertical portions positioned upon said lower platform, a strand carried by said vertical portions, a plurality of cans pivotally mounted upon said strand, distributing means carried by said lower platform in alinement with said cans, a plurality of trip arms pivotally mounted upon the outer periphery of said upper platform, said cans 125 130.

provided with fixedly secured plates extending thereabove, said trip arms being adapted to releasably retain said cans in a set position, and means for operating said trip arms 5 for intermittently releasing said cans for allowing the same to swing downwardly whereby the contents of the cans will be emptied upon the food distributing means

so as to cause the food to be efficiently scattered.
